DESIGN FOR A HAIR CURLER

Edgar Beresford Gilleland, Los Angeles, Calif.

Application April 12, 1935, Serial No. 56,345

Term of patent 3½ years

To all whom it may concern:

Be it known that I, Edgar Beresford Gilleland, a citizen of the United States, residing at Los Angeles, in the county of Los Angeles and State of California, have invented a new, original, and ornamental Design for a Hair Curler, of which the following is a specification, reference being had to the accompanying drawing, forming a part thereof.

I claim:

The ornamental design for a hair curler substantially as shown.

EDGAR BERESFORD GILLELAND.
